DESIGN FOR A CLOTHES STAND

Louis Schweitzer, Detroit, Mich.

Application April 30, 1945, Serial No. 119,453

Term of patent 7 years

(Cl. D80—9)

To all whom it may concern:

Be it known that I, Louis Schweitzer, a citizen of the United States, residing at 489 Robinwood Street, in the city of Detroit, county of Wayne, and State of Michigan, have invented a new, original, and ornamental Design for Clothes Stand, of which the following is a specification, reference being had to the accompanying drawing, forming part thereof.

The figure is a perspective view of a clothes stand, showing my new design.

I claim:

The ornamental design for a clothes stand, as shown.

LOUIS SCHWEITZER.
